SECTIONAL GUIDE ROLL

Bryant Bannister, Mount Lebanon, Pa.

Application March 14, 1933, Serial No. 660,719

4 Claims. (Cl. 308—58)

This invention relates to improvements in sectional guide rolls for rolling mills, and particularly to that type of mill used in the manufacture of seamless pipes and tubes. These guide rolls are power-actuated, and rotate about axes substantially transverse to the axis of the mill and have a peripheral speed in the direction of and greater than the longitudinal speed of a work-piece progressing through the mill.

Guide rolls of this type are generally extremely efficient in operation, once installed, but frequently require replacement due to a desired change in size, wear, and to other difficulties encountered in practice.

In order to replace a guide roll in accordance with present practice, it is necessary to suspend the operation of the mill for a considerable length of time due to the fact that the shafts and bearings associated with these rolls must be entirely removed. In addition, a great deal of labor is necessary to carry out the rather complicated operation, largely because of the weight of the various parts to be handled.

One object of the present invention is to provide a novel guide roll for rolling mills, which is particularly easy to replace, and one which is comparatively cheap to manufacture.

Another object is to provide a novel and efficient mounting for guide rolls.

These and further objects will be apparent after referring to the drawing, in which:

Figure 1 is a sectional elevation of my improved guide roll structure as associated with the outlet end of a conventional rolling mill.

Figures 2 and 3 are detail views of the apparatus of Figure 1.

Figure 4 is a modified form of the invention.

Referring more particularly to the drawing, the numeral 2 indicates a pair of power-actuated work rolls between which, and a mandrel 3, it is desired to operate upon a work-piece 4.

The work rolls 2 are preferably mounted on axes arranged in different horizontal planes and are canted with respect to one another.

A pair of guide rolls 5, having grooved peripheries 5^a, are disposed in the outlet end of the work rolls 2 and are arranged on axes substantially transverse to the axis of a work-piece 4 progressing through the mill. One of these guide rolls 5 is usually positioned above the work-piece and the other below the same, and are rotated in the direction of and at a greater peripheral speed than the longitudinal speed of the work-piece.

The guide rolls 5 of my invention comprise an

annular ring provided with abutments 6, and holes 7 to permit of their being mounted on a suitable driving means. A driving shaft 8 and idler shaft 9 are provided with collars 10 at their aligned and adjacent ends, and rotate within suitable bearings disposed within bearing housings 11, which are connected to bearing housing supports 12 by bolts 13 and nuts 14.

Referring to Figure 3, the shafts 8 and 9 and bearing housings 11 are kept in exact alignment 10 with the supports 12 through the medium of a key 11^b disposed in keyways 11^c in both bearing housing and support.

The guide roll 5 is mounted between the collars 10 and secured thereto by bolts 15 and nuts 16, the abutments 6 of the guide roll contacting with the edges of the collars 10.

In order to permit of the quick and easy removal of the guide roll, the bearing housing of the idler shaft 9 is provided with slots 11^a in lieu of the bolt holes of the bearing for the driving shaft 8. Similarly, the bearing housing support 12 for the idler shaft 9 is provided with slots 12^a which are in practice somewhat smaller than those indicated at 11^a in its associated bearing housing.

Referring to Figure 4, I have disclosed a modification, in which the guide roll 5 is provided with abutments 6 and a comparatively short boss portion 6^a. In this form of the invention the boss 6^a is clamped between the collars 10 which have been recessed as at 10^a to provide a satisfactory seat.

While I have shown and described several specific embodiments of my invention it will be understood that I do not wish to be limited exactly thereto, since various modifications may be made without departing from the scope of my invention, as defined in the following claims.

I claim:

1. In a guide roll construction for seamless tube mills and the like, the combination of a driven shaft, a collar on said driven shaft, an idler shaft in alignment with said driven shaft, rigid means for preventing misalignment of said idler shaft, said idler shaft being movable toward and away from said driven shaft, means for holding said idler shaft against movement, a collar on the end of said idler shaft which is adjacent said driven shaft, a guide roll having its periphery transversely contoured to conform to the periphery of a work-piece to be carried thereby, and means for rigidly maintaining said guide roll between the collars on said driven and idler shafts.
2. In a guide roll construction for seamless tube

- 5 mills and the like, the combination of a driven shaft, a collar on said driven shaft, a bearing in alignment with said driven shaft, rigid means for preventing misalignment of said bearing, said bearing being movable toward and away from said driven shaft, means for holding said bearing against movement, an idler shaft in said bearing, a collar on the end of said idler shaft which is adjacent said driven shaft, a guide roll having its periphery transversely contoured to conform to the periphery of a work-piece to be carried thereby, said guide roll being annularly recessed on both of its sides to seat in the annular recesses in the collars on said driven and idler shafts, and means for rigidly maintaining said guide roll between said collars, said last named means being spaced from those portions of the collars which contact 10 said guide roll.
- 10 4. In a cross-rolling mill, the combination with a pair of helically acting cross rolls, of a guide disc arranged to act between said rolls, two axially aligned shafts provided with opposed flanges 15 at their adjacent ends, means for removably attaching said disc to said flanges between their adjacent faces, and bearings each rotatably supporting one of said shafts, one of said bearings being mounted for axial movement with relation 20 to the other to separate said shafts for the removal of said disc from between them.
- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280
